UNITED STATES PATENT OFFICE.

GEORGE F. DAWSON, JOHN MYERS, AND JOHN SMITH, OF BRADFORD,
COUNTY OF YORK, ENGLAND.

LOOM.

SPECIFICATION forming part of Letters Patent No. 236,994, dated January 25, 1881.

Application filed September 15, 1880. (No model.) Patented in England March 5, 1880.

To all whom it may concern:

Be it known that we, GEORGE FREDERICK DAWSON, JOHN MYERS, and JOHN SMITH, residing in Bradford, in the county of York, 5 England, and subjects of the Queen of Great Britain and Ireland, have invented certain Improvements in Looms for Weaving, (for which we obtained a patent in Great Britain, No. 1,105, dated March 5, 1880,) of which the 10 following is a specification.

The object of this invention is to arrange the brake apparatus connected with warp-beams in looms for weaving in such a manner that when the healds are opening the shed 15 in the warp for the shuttle to pass through the pressure on the brake is relieved and the tension on the warp-threads reduced to such a degree that there is no material stretching of the warp-threads, and in case the shuttle 20 should by any means stop in the shed the breakage of warp-threads is greatly reduced; also, to so arrange the brake apparatus that the warp-beam is held firm and rigid at each 25 pick of the loom at such time when what is technically termed the "going part" or lay 30 is beating up the weft just delivered from the shuttle.

Such being the objects of this our invention, we will describe the particulars there- 35 of, aided by the accompanying drawings, in which—

Figure 1 represents a transverse sectional elevation of a loom, showing such portions of the loom as are required to make clear our invention. Fig. 2 is a plan of one end of a loom 40 fitted with our improved brake apparatus, and Fig. 3 is an enlarged view of the brake-clips and end of brake-lever.

Similar letters are used in the several figures in indicating identical parts.

We will describe our apparatus as applied to one end of the warp-beam. At the same time we wish it to be understood that we apply the apparatus at both ends of the warp-beam in wide looms or when weaving heavy goods.

The warp-beam A is mounted in the usual manner, and around the ordinary metal collar, near the end of beam A, we place brake-clasps B, which fit the circumference of the said collar. These clasps or clips B are

jointed at C, and have long taper projecting pieces at D, which pass through a hole formed near the end of lever G. In this hole are also mounted two small pulleys, H, the circumferences of which are in contact with projecting pieces D. One end of the lever G is carried by pin J, which serves as its fulcrum, and the lever is of such a length that the other end is underneath what is technically termed the "going part" or lay K. At the under side of the going part K we secure a small pulley, L, which, at each beat up of the weft, comes in contact with the end of lever G and forces the lever down. The small pulleys H 55 pass down the taper projections D and nip the same together, and the brake-clips B hold the warp-beam A tight during the beat up and until the return of the going part, when the lever will rise and reduce the pressure of 60 the brake-clips B on the collar at end of warp-beam A, reducing the tension of the warp to such a degree that the healds can open the shed without materially stretching or damaging the warp-threads. The light spiral spring 65 M is applied to lever G, in order to prevent the lever from jumping on the return-stroke of the going part.

We are aware that it has heretofore been proposed to combine a brake with a warp-beam, the brake being applied through the medium of the lay at each beat up. This, therefore, we do not desire to claim, broadly; but

We claim as our invention—
The combination of the frame and lay of a 85 loom and operating mechanism with the warp-beam, the brake being applied through the medium of the lay at each beat up. This, therefore, we do not desire to claim, broadly; but

In testimony whereof we have signed our names to this specification in the presence of 90 two subscribing witnesses.

GEO. F. DAWSON.
JOHN MYERS.
JOHN SMITH.
